(57) **CLAIM**

The ornamental design for a storage shelf, as shown and described.

DESCRIPTION

In a preferred embodiment, the nature of this product is as a shelving cove suitable for use with shower enclosures.

FIG. 1 is a right, top, front perspective view of a storage shelf according to my new design;

FIG. 2 is a front elevational view thereof;

FIG. 3 is a right side elevational view thereof, the left side elevational view thereof being a mirror image of the right side shown;

FIG. 4 is a top plan view thereof;

FIG. 5 is a bottom plan view thereof; and

FIG. 6 is a rear elevational view thereof; and,

FIG. 7 is a sectional view taken along line 7—7 of FIG. 2.
